A. B. Barstow, of Providence, R. I.
Letters Patent No. 1089, Dated March 22, 1859.

The Schedule referred to in these Letters Patent and making part of the same.

To all persons to whom these presents shall come,

Be it known that I, A. G. Barstow, of Providence, in the County of Providence and State of Rhode Island, have invented a new design for the side plate of a cooking-stove and I hereby declare that the said new design is fully described and represented in the following Specification and accompanying drawings to which reference is herein after made.

The figures of the accompanying plate of drawings represent my new design.

Fig. 1. is an elevation of the side plate.

Fig. 2. is a transverse vertical section taken in the plane of the line A. B. fig. 1.

The oven door a. a. of the side plate is ornamented with a raised moulding, b. b. around its sides and panels c. c. with raised waved mouldings d. d.

The centre of the large door a. a. is ornamented with raised waved mouldings e. e. and raised figures f. f.

The small doors K. K. are ornamented the same as the large door a. a. Over the top of the large door a. a. is a raised tablet g. g.

Having thus described my new design, I shall state my claim as follows.

What I claim as my invention or production and desire to have secured to me by Letters Patent, is the new design for the side plate of a cooking-stove consisting of the ornamental configurations herein above described and represented in the drawings.
